UNITED STATES PATENT OFFICE

112,023

DESIGN FOR AN IGNITION COIL HOUSING

Gunnar R. C. Martinsson, Riverside, Ill., assignor
to Elsbert Manufacturing Company, Inc., Chi-
cago, Ill., a corporation of Illinois

Application March 21, 1938, Serial No. 75,985

Term of patent 14 years

To all whom it may concern:

Be it known that Gunnar R. C. Martinsson, a citizen of the United States, residing at Riverside, in the county of Cook and State of Illinois, has invented a new, original, and ornamental Design for an Ignition Coil Housing, of which the following is a specification, reference being had to the accompanying drawing, forming part thereof.

In the drawing,

Figure 1 shows an isometric view of the ignition

coil housing taken from the mounting bracket side thereof.

Figure 2 shows an elevation of the coil housing.

Figure 3 is a top view looking down upon the coil housing.

I claim:

The ornamental design for an ignition coil housing, as shown.

GUNNAR R. C. MARTINSSON.
